Primary Examiner — Terry A Wallace(74) *Attorney, Agent, or Firm* — McKee, Voorhees & Sease, P.L.C.(57) **CLAIM**

The ornamental design for a spice bottle holder, as shown and described.

DESCRIPTION

FIG. 1 is a front perspective view of a spice bottle holder showing my new design.

FIG. 2 is a rear perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a side elevation view thereof, the opposite side being a mirror image.

FIG. 8 is a front perspective view of a second embodiment of FIG. 1.

FIG. 9 is a rear perspective view of FIG. 8.

FIG. 10 is a front elevation view of FIG. 8.

FIG. 11 is a rear elevation view of FIG. 8.

FIG. 12 is a top plan view of FIG. 8.

FIG. 13 is a bottom plan view of FIG. 8; and,

FIG. 14 is a side elevation view of FIG. 8, the opposite side being a mirror image.

The broken lines are for illustrative purposes only and form no part of the claimed design.
